UNITED STATES PATENT OFFICE.

OTTO PETERMANN, OF GROTON, NEW YORK, ASSIGNOR TO CORONA TYPEWRITER COMPANY, INCORPORATED, A CORPORATION OF NEW YORK.

TYPE-WRITING MACHINE.

1,121,042.

Specification of Letters Patent.

Patented Dec. 15, 1914.

Application filed February 6, 1912, Serial No. 675,771. Renewed October 31, 1914. Serial No. 869,715.

To all whom it may concern:

Be it known that I, OTTO PETERMANN, a citizen of the Republic of Switzerland, and a resident of Groton, county of Tompkins, 5 and State of New York, have invented certain new and useful Improvements in Type-Writing Machines, of which the following is a full, clear, and exact description.

This invention relates more particularly 10 to mechanism for vibrating the ribbon transversely of a platen to cover and uncover the printing point of visible or front-strike typewriting machines.

The primary object of the invention is to 15 provide simple and efficient means adapted to operate the ribbon vibratory mechanism to adapt the ribbon to have a plurality of fields or zones of different colors thereon and the said means adjusted in such a way 20 that the ribbon mechanism may be made to remain inactive in order that the machine may be used for the purpose of making stencils.

Other objects of the invention are to provide 25 simple and efficient means whereby a ribbon may be moved across the platen to cover and uncover the printing point and the ribbon held normally below said printing point; and to provide simple and efficient means whereby the ribbon vibratory 30 mechanism may be operated to vary the extent of throw of the ribbon to present either of two fields of different colors or different parts of the ribbon having the same color 35 for printing purposes.

Another object of the invention is to provide 40 a simple and efficient device which may be manually operated and located adjacent to a part of the ribbon mechanism and capable of adjustment so that in one position it will operate the ribbon mechanism to cause one field of the ribbon to be presented for printing purposes, in another position to present another field for printing purposes, and in 45 a third position will not operate the ribbon vibratory mechanism at all, thereby causing said mechanism to remain inactive while the machine may be otherwise operated in the usual way.

A further object of the invention is to 50 provide simple and efficient means for holding the actuating device in an adjusted position, and for determining what field of the ribbon is being presented for printing 55 purposes.

A still further object of the invention is to provide simple and efficient means which may be used in connection with various kinds of machines.

With these and other objects in view, the 60 invention will be hereinafter more particularly described with reference to the accompanying drawings, which form a part of this specification, and will then be pointed out in the claims at the end of the description. 65

In the drawings, Figure 1 is a fragmentary front elevation of the upper part of a typewriting machine showing one form of the invention applied thereto. Fig. 2 is a 70 longitudinal section of a machine, partly diagrammatic and partly in elevation, showing how the invention may be operated as the keys are depressed. Fig. 3 is a sectional plan view taken on the line III—III 75 of Fig. 1; and Figs. 4 and 5 are fragmentary views showing other forms of parts of the invention.

While the invention is more particularly intended for use in connection with a type 80 machine wherein the platen and carriage is folded or shifted forward to adapt the machine to be made more compact than when in use, it will be understood that the said invention may be applied to various 85 kinds and constructions of typewriting or similar machines.

The frame 10 may be of sheet metal and extending transversely between the sides 11 thereof are a plurality of rods 12. These 90 rods are adapted to support key-levers 13 which are arranged in groups or banks and are suspended from said rods. The key-levers may be held against depression by springs 14 and at their inner ends may be 95 connected by a link 15, a part only of which is shown, to the type-bars to operate the latter for printing purposes. A universal bar 16 extends along and over the key-levers and is adapted to be actuated by each key-lever as the same is depressed, and said universal bar has arms 17 which are pivoted at 18 to the arms 19 of bell-crank levers 20. The bell-crank levers 20 are located on opposite sides of the machine and each lever is 100 pivoted at 21 to one of the sides of the machine frame, and said levers have ends 22 entering slots 23 arranged in vertically extending arms 24. The arms 24 are also located on opposite sides of the machine and 110

are pivotally held to a transversely extending rod 25 at their lower ends, and at their upper ends are connected by a bar 26 which may be separate from, or integral with the arms 24. As the key-levers are depressed, the universal bar 16 will have a vertical movement imparted thereto and this will rock the bell-crank levers 20 on their pivots which will rock the arms 24 and bar 26 connecting said arms. The arms 24 and bar 26 form what may be termed an escapement or other rocking frame as the said bar usually serves as a means to operate a part of the escapement mechanism, which latter is not shown as it forms no part of the present invention.

Adjacent to the arms 24 are slides or posts, not shown, which may be connected to the transversely extending rod 25, and this rod may be connected to an arm 27 forming a part of a platen shift mechanism. The slides are each connected to one of the bars or members of a two-part foldable support 28, the members of which may be pivoted at 29, and mounted on one part of said support is a carriage bed 30. A carriage 31 is adapted to travel along said bed, and on said carriage is mounted a platen 32. The carriage and bed and mechanism mounted on said bed are adapted to be moved with the foldable part of the support to place the platen and carriage in overhanging relation to the keyboard or otherwise as desired. The parts thus far described may be of the usual or of any preferred construction.

A bracket 33 has a curved body portion or arm 34 and a base plate 35, the latter being rigidly secured under the carriage bed, said arm 34 extending forward and upwardly in front of the platen 32. A ribbon vibrator 36 is pivoted by a screw 37 or otherwise to the bracket arm 34. This vibrator may be in the form of a bell-crank lever, one arm of which, as the arm 38, extends normally in substantially a horizontal plane lengthwise of the platen and in front thereof, and is provided with an end or loop portion 39 through which the ribbon 50 is adapted to pass or be threaded in the usual way. The loop portion 39 is substantially C-shaped having an open part 40 for the insertion or removal of the ribbon at will, and said loop portion when the ribbon 55 vibrator is operated, as will be presently described, imparts a vertical movement to the ribbon so as to cover and uncover the printing point, the normal position of said loop or end of the vibrator being such as to hold 60 the ribbon below the printing point. The end 39 of the vibrator is adapted to move at the rear of an aliner 41 which is adapted to position the type-heads, the said aliner being of any suitable construction. The arm 42 of the ribbon vibrator or bell-crank lever

extends downward substantially vertically and has an opening 43 which is adapted to be engaged by the end of an arm 44 of a lever 45. This lever 45 is pivoted at 46 under the carriage bed 30 and has an arm 47 angularly arranged with respect to the arm 44. The lever 45 is adapted to move horizontally and has its arm 47 connected to one end of a spring 48, the other end of said spring being held to a pin 49 located under the carriage bed. The spring 48 tends normally to force the lever 45 to move the end 39 of the ribbon vibrator downward, as shown in Fig. 1, and in case the ribbon vibrator should be actuated, as will be presently described, on the depression of a key, the spring 48 as soon as the key is released will return the ribbon vibrator to its normal position.

To permit stencils to be made and to actuate the lever 45 and through it the ribbon vibrator owing to the connection between the arm 44 of the lever 45 and the arm 42 of the ribbon vibrator or bell-crank lever 36, various means may be employed. As shown, the lever 45 is provided with a projecting portion 50 having a lug or part 51, and this part is located within the path of movement of a device 52. The device 52 is pivoted by a screw 53 or otherwise to the rocking bar 26 and said device is in the form of a lever having a handle portion or finger part 54 by which said device may be moved on its pivot. The device 52 has a projection or engaging part 55 and a part 56, and arranged between said parts is a space or opening 57. The parts 55 and 56 are adapted to be brought into position to engage the lug or projecting portion 51 of the lever 45, and owing to the relatively different distances of the parts 55 and 56 from the pivot screw 53, will impart different throws to the lever 45 and consequently to the ribbon vibrator 36. The arms 24 and the bar 26 connecting the same will have the same extent of movement as each key-lever is depressed, and by properly proportioning the relative lengths of the parts 55 and 56 of the device 52, different fields of the ribbon may be presented to the printing point. If the lever or device 52 is moved toward the right to cause the projection 56 to engage the lug 51, a greater throw will be given the ribbon vibrator and consequently the ribbon operated thereby. If the lever 52 by means of the finger part 54 is moved to the extreme left position so that the part 55 will engage the part 51 of the lever 45, a less throw will be given the ribbon vibrator through the lever 45 because the said part 55 will not engage and operate the lever 45 as soon after one of the keys is depressed as is the case with the projection 56. On the other hand, if the lever or device 52 is in a central or neutral position to place the opening or space 57 in alignment with the lug or projection 51, the plate

or bar 26 may be moved by depressing the keys as usual without operating the lever 45 and ribbon vibrator as the said device at this time will not engage the part 51, thus the 5 lever 45 and ribbon vibrator will remain inactive to adapt the keys to be operated in the usual way to permit stencils to be made or the invention to be otherwise used, though the parts may be so constructed and arranged 10 that a movement may be imparted to the ribbon but not enough to cover the printing point.

A bracket or member 58 is held to the plate or bar 26 under the lever or device 52 and this member may be of steel or yielding material to adapt the outer part thereof to yield during the movement of the finger part of the device 52. The outer part 59 of the bracket or member 58 may be corrugated to provide three recesses 60, 61 and 62. In the intermediate position, the handle portion 54 of the device 52 will engage the intermediate recess so as to hold the same in this position and when moved 25 to the right will engage the recess 62, and when moved to the left, the recess 61. The recesses form raised parts between the same so that by forcing the lever to either side, it will ride over the raised parts causing 30 the bracket or member to yield, and the latter will immediately spring back into position again and thereby hold the device or lever 52 in either of its three positions. By this means, the device 52 by remaining in a central or neutral position, permits the ribbon to remain inactive and by moving the device to either side of the central or neutral position, will cause different fields of the ribbon to be presented 35 to the printing point according to which direction the device is moved.

An indicator or device 63 may be held to the bar 26 and this device may be in the form of a bracket with a plate-like part 64. The part 64 may have its edges folded over and adapted to form a receiver for a strip 65 on which may be indicated any suitable color or colors as red, white and black, to represent the red field of the ribbon, the black field of the ribbon, and the white for the inactive or stenciling position of the ribbon. The indicating colors of the indicating device 63 may be directly printed on paper and then placed in the bracket, or it may be on the other material, and if on paper, the latter may be covered by mica, celluloid, or any other cover to protect the same.

The invention will be readily understood 60 from the foregoing description when taken in connection with the accompanying drawings. The ribbon may be threaded in the end 39 of the ribbon vibrator in the usual way and when one of the key-levers 13 is depressed, the universal bar 16 will operate

the bell-crank levers 20 and through them the arms 24 and bar 26. This will reciprocate the device 52 back and forth and in the position shown in the drawings, the said device will not actuate the lever 45, and, therefore, the ribbon vibratory mechanism will remain inactive and the ribbon remain in its normal position below the printing point. If the handle or part 54 of the device 52 is moved to the right, the part 56, on depression of the key-lever, will engage the lug or projecting part 51 of the lever 45 and move the same against the action of the spring 48. This will cause the arm 44 of the lever 45 to move the arm 42 of the ribbon vibrator and thereby carry the ribbon over the printing point, which, as indicated, would be the red field, and as soon as the key is released, the spring 48 will restore the vibrator and lever 45 to their normal position. If the device 52, by the handle portion 54, is moved to place the part 55 in alignment with the projecting part 51, the said part 55 will engage the part 51, as already explained, but will move the lever 45 to a less extent and consequently will move the ribbon vibrator and ribbon to a less extent, in which case it will present another field to the printing point, which, as shown, will be a black field, though the colors and character of the fields may vary.

In Fig. 4, the plate 26 has a slide or device 66 thereon which is adapted to move lengthwise of the rocking bar 26. This slide 66 has a slot 67 through which passes the stems of screws 68 and 69. The slide 66 has a projecting part 70 which is connected to a hand-operated lever 71, the latter being provided with a slot 72 which is engaged by a pin 73 carried by said part 70. The lever 71 is pivoted at 74 and when moved on its pivot through a finger part 75, will cause the slide 66 to be moved to the position shown, in which the screw 69 serves as a guide and stop, or if given an extreme movement to the left will move the slide until it is stopped by the pin or screw 68. The slide may be moved to a position intermediate of these two extreme throws. A lug 76 projects outward from the slide and this lug is adapted to engage an arm 77 of a lever 78. This lever 78 is pivoted at 79 to the carriage bed and has its arm 80 normally forced against a stop 81 by a spring 82, the latter being connected at one end to a pin 83, and its other end to the lever 78. The arm 80 of the lever may be connected by a link 84 to the lower arm 42 of the ribbon vibrator. If the bar 26 is rocked, as already described, the lug 76 will engage the arm 77 of the lever 78 to move the same on its pivot, thus causing the ribbon vibrator to be operated to move the ribbon over the printing point, the ribbon vibrator and lever 78 being restored to its normal posi-

tion by the spring 82. If the lever 71 is moved to the left until the slide 66 is stopped by the screw 68, the projection 76 will engage the arm 77 of the lever 78 and operate the same in a manner already described, except to a different extent. In this position, the throw of the lever will be greater owing to the point of engagement being closer to the pivot 79, thus a different field of the ribbon will be presented for printing purposes. If the lever 71 is moved to an intermediate position, the projection 76 may be caused to enter a slot or recess 85 in the arm 77 of the lever 78, thus permitting the bar 26 to rock without actuating the lever 78, and, therefore, the ribbon mechanism will in this case remain inactive. By shifting the lever 71 to any position intermediate of these points, different fields of the ribbon may be presented so that if the ribbon is of a single color, substantially the entire surface of the ribbon may be utilized.

Fig. 5 differs from the construction shown in Figs. 1 to 3 in that the two engaging parts are adjacent to each other and no space is required in this case to permit the ribbon to remain inactive. In this construction, the inactive position is one of the extreme throws of the device. As shown, the part 51 of the lever 45 is adapted to be engaged by either of the parts 86 or 87 of the hand-operated lever or device 88. This lever 88 is pivoted at 89 to the transversely extending bar 26, and in the position shown, the part 86 will engage the part 51 of the lever 45 imparting thereby a movement to the ribbon when the key is depressed as hereinbefore described. If the lever or device 88 is moved to the right to cause the engaging part 87 to be in alignment with the part 51, and one of the keys is depressed, the bar 26 will cause the device 81 to rock therewith and on engagement of the part 87 with the part 51, will give a greater throw to the ribbon vibrator and ribbon. By moving the device to the left so that neither of the parts 86 or 87 will engage the part 51 of the lever 45 when the bar 26 is rocked, the said lever 45 will remain inactive and consequently the ribbon will be held below the printing point. In this construction, the position of the lever 88 for stenciling purposes is at one of the extreme movements of said lever while in the construction shown in the other figures, the position for stenciling is intermediate the extreme movements.

From the foregoing, it will be seen that simple and efficient means is provided whereby different fields or zones of a ribbon may be presented for printing purposes, or the ribbon made to remain inactive in order that stencils may be made; that simple mechanism is provided for operating the ribbon to cover or uncover the printing

point; that simple means is provided whereby the ribbon vibrating mechanism may be actuated to present different fields for printing purposes; and that said invention may be applied to typewriting or similar machines of various kinds.

Having thus described my invention, I claim as new and desire to secure by Letters Patent:—

1. In a typewriting machine, the combination of a support, a carriage mounted to travel lengthwise of said support, a bracket held to said support and extending upward in front of the carriage, a ribbon vibrator pivotally held to said bracket, a rocking bar, and means mounted on said bar adapted to impart different throws to said vibrator or to permit the vibrator to remain inactive.

2. In a typewriting machine, the combination of a support, a carriage mounted to travel lengthwise of said support, a platen supported in the carriage, a bracket held to said support, a ribbon moving device held to said bracket at one side of the printing point and in substantially a horizontal plane therewith, and means adapted to impart different throws to said device.

3. In a typewriting machine, the combination of a support, a carriage mounted to travel lengthwise of said support, a ribbon moving device, bodily movable and adjustable means adapted to impart different throws to said ribbon moving device or to permit the same to remain inactive, and means movable with the bodily movable means for locking said bodily movable means in its various adjustments.

4. In a typewriter in which the platen and carriage are adapted to be brought into compact relation to the keyboard, the combination of a support, a bracket mounted on said support, a ribbon vibrator held to said bracket and adapted to impart vertical movements to the ribbon, a rocking element, a pivotally held finger lever mounted on said rocking element and adapted to be placed in different positions to move the vibrator different distances or to permit the same to remain inactive, and means whereby the lever may be held in any one of its adjusted positions.

5. In a typewriter in which the platen and carriage are adapted to be folded over the keyboard, the combination of a support, a ribbon vibrator held to said support and adapted to impart vertical movements to the ribbon, a rocking bar, a pivotally held finger lever mounted on said rocking bar and adapted to be placed in different positions to move the vibrator different distances or to permit the same to remain inactive, and means whereby the lever may be held in any one of its adjusted positions.

6. In a typewriter, the combination of a support, a carriage movable along said sup-

port, a bell-crank ribbon vibrator adapted to impart vertical movements to the ribbon, a rocking element, a pivotally held finger lever mounted on said rocking element adjacent to the carriage and adapted to be placed in different positions to move the vibrator different distances or to permit the same to remain inactive, and means whereby the lever may be held in any one of its adjusted positions.

7. In a typewriter in which the platen and carriage are adapted to be brought in close relation to the keyboard when not in use, the combination of a support for the carriage, a ribbon vibrator, a rocking element, a pivotally held finger lever mounted on said rocking element and adapted to be placed in different positions to move the vibrator to different positions or to permit the same to remain inactive, and means wholly mounted on said rocking element for holding said lever in any one of its adjusted positions.

8. In a typewriting machine, the combination of a ribbon vibrator, a rocking member, a member held to said rocking member and provided with corrugated portions, a pivotally held finger lever mounted on said rocking member and having a part thereof engaging said corrugated portions to hold the same in various adjustments, said lever serving as the actuating means for the vibrator, and means whereby the position of the lever may be indicated to determine the extent of movement to be given to the ribbon vibrator or whether or not the said ribbon vibrator is to remain inactive.

9. In a typewriting machine, the combination of a ribbon vibrator, a rocking member, a member held to said rocking member and provided with corrugated portions, a pivotally held finger lever for operating the vibrator mounted on said rocking member and having a part thereof engaging said corrugated portions to hold the same in various adjustments, and means to indicate the position of the lever and thereby the movement of the ribbon vibrator.

10. In a typewriting machine, the combination of a ribbon vibrator, a rocking member, a member held to said rocking member and provided with corrugated portions, and a pivotally held vibrator operating finger lever mounted on said bracket and having a part thereof engaging said corrugated portions to hold the same in various adjustments.

11. In a visible writing typewriter in which the carriage and platen is foldable into overhanging relation to the keyboard, the combination of a carriage bed along which a carriage is adapted to travel, a bracket secured to said carriage bed and projecting upward in front of the platen, a bell-crank lever for actuating the ribbon to move

the same to cover and uncover the printing point and pivotally held to said bracket, a reciprocatory member, and adjustable means mounted on said reciprocatory member adapted to move the vibrator different distances to present different fields to the printing point or to permit the vibrator to remain inactive.

12. In a visible writing typewriter in which parts thereof are foldable to make the same compact when not in use, the combination of a carriage bed, a bracket secured to said carriage bed and projecting upward in front of the platen, a bell-crank for actuating the ribbon to move the same to cover and uncover the printing point and pivotally held to said bracket, a reciprocatory bar, and an adjustable finger lever mounted on said reciprocatory bar and adapted to move the vibrator different distances to present different fields to the printing point or to permit the vibrator to remain inactive.

13. In a typewriting machine, the combination of a ribbon vibrator having a horizontally extending arm, the end of which is adapted to engage the ribbon and a substantially vertically arranged arm, a support to which said vibrator is pivoted, a carriage bed, a lever pivotally held to move horizontally under said carriage bed and having a part thereof engaging the vibrator to operate the same, a rocking bar, key-levers adapted to operate said bar when depressed, and means held to said rocking bar and adapted to engage said lever.

14. In a typewriting machine, the combination of a ribbon vibrator having a horizontal extending arm, the end of which is adapted to engage the ribbon and a substantially vertically arranged arm, a support to which said vibrator is pivoted, a lever pivotally held to move horizontally and connected to the vibrator to operate the same, and means for operating said lever to move the vibrator different distances.

15. In a typewriting machine, the combination of a ribbon vibrator, a reciprocatory bar, key-operated levers adapted to operate said bar when depressed, and a device pivotally held to said reciprocatory bar and adapted to operate said vibrator.

16. In a typewriting machine, the combination of a ribbon vibrator, a bodily movable bar, key-operated levers adapted to operate said bar when depressed, and a movable device held to said bar and having a lateral adjustment thereon and adapted to operate the vibrator different degrees.

17. In a typewriting machine, the combination of a vibrator having a horizontally extending arm, the end of which has a loop and is adapted to engage the ribbon and a substantially vertically arranged arm, a support to which said vibrator is pivoted, a carriage bed, a lever pivotally held to move

horizontally on said carriage bed and having a part thereof directly engaging the lever to operate the same, a rocking bar, key-operated levers adapted to operate said bar when depressed, and a movable device held to said rocking bar and having means for engagement with the horizontally movable lever.

18. In a typewriting machine, the combination of a support, a bell-crank lever forming a ribbon vibrator and having one arm provided with an opening, a horizontally movable lever having an arm thereof adapted to enter the opening of the bell-crank lever, and means for operating said horizontally movable lever.

19. In a typewriting machine, the combination of a support, a bell-crank lever forming a ribbon vibrator and having one arm provided with an opening, a pivotally held and horizontally movable lever having an arm thereof adapted to enter the opening of the bell-crank lever, and means for operating said horizontally movable lever.

20. In a typewriting machine, the combination of a support, a ribbon vibrator mounted on the support, a horizontally movable lever also mounted on the support and connected to operate the vibrator, and means independent of the support and separable from the vibrator and adapted to operate said vibrator or permit the same to remain inactive.

21. In a typewriting machine, the combination of a ribbon vibrator, a support to which said ribbon vibrator is held, a lever adapted to operate the vibrator, a pivotally held device separable from the support and lever and having parts located at relatively different distances from its pivot and adapted to engage a part of the lever, movable means to which said device is pivoted, and means for holding the device in different positions.

22. In a typewriting machine, the combination of ribbon vibrating mechanism, a rocking bar, a pivotally held device mounted on the rocking bar and having means whereby the ribbon vibrating mechanism may be operated to different extents during the movement of said device or to remain inactive during such movement, a handle portion for operating said device and formed as a part thereof, and a bracket

movable with the device and having a part 55 with engaging portions adapted to hold said device in its different adjusted positions.

23. In a typewriting machine, the combination of ribbon vibrating mechanism, a pivotally held and bodily movable device 60 having means whereby the ribbon vibrating mechanism may be operated to different extents during the movement of said device or to remain inactive during such movement, and a bracket movable with said device and 65 having a yielding part with recessed portions adapted to hold said device in its different adjusted positions.

24. In a typewriting machine, the combination of ribbon vibrating mechanism, a 70 pivotally and horizontally adjustably held device having means whereby the ribbon vibrating mechanism may be operated to different extents during the movement of said device or to remain inactive during 75 such movement, and a bracket having recessed portions adapted to hold said device in its different adjusted positions and to which the device is pivoted.

25. In a typewriting machine, the combination of ribbon vibrating mechanism, a device adapted to operate said ribbon vibrating mechanism to different extents or to permit said mechanism to remain inactive, means to which said device is held adapted 85 to hold said device in different positions, and an indicator comprising a plate portion, and means held on said plate portion to indicate the position of the device and the field of the ribbon to be presented to the 90 printing point.

26. In a typewriting machine, the combination of ribbon vibrating mechanism, a device adapted to operate said mechanism to different extents or to permit said mechanism to be inactive, and a bracket forming 95 a support for the device and having an indicator comprising a plate portion, and means to indicate the position of the device and the field of the ribbon to be presented to 100 the printing point.

This specification signed and witnessed this 23rd day of January A. D. 1912.

OTTO PETERMANN.
